(57) **CLAIM**

The ornamental design for a closure, as shown and described.

DESCRIPTION

FIG. 1 is an upper, right front, corner isometric view of a first embodiment of a closure showing my new design with the closure in the closed condition, and the closure is adapted to be mounted on a bottle or other container (not illustrated);

FIG. 2 is an upper, front isometric view thereof;

FIG. 3 is a lower, right front, corner isometric view thereof; and,

FIG. 4 is a lower, left rear, corner isometric view thereof with the lid closed.

The broken line showing of a hinge depicts environment only and forms no part of the claimed design.
